UNITED STATES PATENT OFFICE.

WILLIAM PORTNER, OF RED LION, PENNSYLVANIA.

CIGAR-PRESS.

SPECIFICATION forming part of Letters Patent No. 376,963, dated January 24, 1888.

Application filed August 1, 1887. Serial No. 245,840. (No model.)

To all whom it may concern:

Be it known that I, WILLIAM PORTNER, of Red Lion, in the county of York and State of Pennsylvania, have invented certain new and useful Improvements in Cigar-Presses; and I do hereby declare that the following is a full, clear, and exact description of the invention, which will enable others skilled in the art to which it appertains to make and use the same, reference being had to the accompanying drawings, and to the letters of reference marked thereon, which form part of this specification.

The object and nature of my invention will be fully set forth in the following specification and claims.

In the drawings, Figure 1 is a perspective view of my improved cigar-press. Figs. 2 and 3 are detached details, and Fig. 4 is a sectional view of the top rail on the line *x x* of Fig. 1.

Similar letters indicate similar parts in the respective figures.

A is a bed-plate, which, with the posts B B and the top rail, C, constitutes the main frame of my improved press. These parts are all rigidly connected together in any well-known manner. At each end of the frame are castings D, which are securely bolted to the bed-plate A and the rail C and serve to brace and strengthen the frame. These castings D are provided with ratchet-teeth *d*, for the purpose hereinafter mentioned.

E E are castings provided on each side with ratchet-teeth *e*, similar to the teeth of the castings D. The castings E are let into the bed-plate A, and are firmly secured thereto by screws or otherwise, and their upper ends abut against the under side of the top rail, C. The upper ends of these castings E are provided with slots *e'*, for the purpose hereinafter described.

The rail C is provided with a T-shaped groove, *c*, (see Fig. 4,) which extends nearly the entire length of the rail. This groove is for the reception of the screw F and nut *f*, the nut *f* being supported by means of strips *c'*, which are firmly secured to the under side of the rail C. These strips also serve as braces to the upper ends of the castings E, to prevent them from spreading.

G G are followers, to the upper side of each

of which is secured a block, G', to which is also secured a top or cover, G". This block and its top or cover are adapted to fit between the castings D and E or between two of the 55 castings E, and they are provided at each end with slots *g*, for the reception of the ratchet-teeth *d* and *e*.

The block G' is recessed or cut out in a suitable manner for the reception of the latches 6-*g*' *g*', the spiral spring *g*², and the levers *g*³. (See Fig. 2.) The latches slide in suitable grooves, and are held normally in engagement with the ratchet-teeth by means of the spring *g*². The levers *g*³ are pivoted at one end to the 65 block G', and their free ends extend outward beyond the block. They are also attached to the latches *g*' in such a way that on pressing the levers toward each other the latches will be drawn out of engagement with the ratchet- 70 teeth. The top or cover G" serves to keep the latches and spring in position, and also serves as a bearing-surface for the screw F.

H H represent molds for cigars.

The operation is as follows: The follower G 75 can be suspended in any position by means of the spring-latches *g*' engaging the ratchet-teeth *d* and *e*. When the desired number of molds have been placed in the press, the follower is lowered and pressure applied by 80 means of the screw F, the spring-latches sliding over the inclined faces of the ratchet-teeth as the follower is being pressed down. When sufficient pressure has been applied, the screw can be raised, and the latches will securely hold the follower in position by engaging with the ratchet-teeth. By sliding the screw F and the nut *f* along the T-shaped groove *c*, the slots *e'* in the upper end of the castings allowing the end of the screw to pass, 85 the screw can be used to apply pressure to the follower in the next press, and so on. It will be seen that one screw can be utilized for any number of presses, and by means of the spring-latches the followers can be held in position 90 as long as it is necessary to have the pressure applied to the molds.

When it is desired to remove the molds from the press, the latches may be released from engagement with the ratchet-teeth by pressing 100 the levers *g*³ toward each other, and the follower can then be raised and will be suspended

by again allowing the latches to engage with the ratchet-teeth.

Having thus fully described my invention, what I claim, and desire to secure by Letters 5 Patent of the United States, is—

1. In a cigar-press, the combination, with the main frame, the top rail of which is provided with a T-shaped groove, of the castings D and E, rigidly secured to said frame 10 and having the ratchet-teeth d and e, and the follower G, having spring-latches to engage with the said ratchet-teeth, substantially as specified.

2. In a cigar-press, the combination, with 15 the main frame, the top rail of which is provided with a T-shaped groove, of the screw F and nut f, adapted to slide in said T-shaped groove, substantially as specified.

3. In a cigar-press, the combination, with 20 the main frame, the top rail of which is provided with a T-shaped groove, of the castings

D and E, rigidly secured to said frame and having the ratchet-teeth d and e, the screw F and nut f, adapted to slide in the said T-shaped groove, and the follower G, having spring- 25 latches adapted to engage with the teeth on the castings, substantially as specified.

4. In a cigar-press, the combination, with the main frame, the top rail of which is provided with a T-shaped groove, of the castings E, provided with ratchet-teeth and having slots at their upper ends, and the screw F and nut f, substantially as and for the purpose specified. 30

In testimony that I claim the foregoing as 35 my own I affix my signature in presence of two witnesses.

WILLIAM PORTNER.
